[57] CLAIM

The ornamental design for a combined sight installation and alignment tool for hand guns, as shown and described.

DESCRIPTION

FIG. 1 is a perspective view of a combined sight installation and alignment tool for hand guns showing my new design;

FIG. 2 is a top plan view thereof;

FIG. 3 is a left side elevational view thereof;

FIG. 4 is a front elevational view thereof, the rear view being a mirror image;

FIG. 5 is a right side elevational view thereof; and,

FIG. 6 is a bottom plan view thereof.

FIG 1

FIG 2

FIG 3

FIG 4
